UNITED STATES PATENT OFFICE.

RICHARD BUERK, OF SCHWENNINGEN, GERMANY.

COUNTING-MACHINE.

No. 922,663.

Specification of Letters Patent.

Patented May 25, 1908.

Application filed December 10, 1908. Serial No. 347,183.

To all whom it may concern:

Be it known that I, RICHARD BUERK, citizen of the German Empire, residing at Schwenningen, in the Kingdom of Württemberg, German Empire, have invented certain new and useful Improvements in Counting-Machines; and I do hereby declare the following to be a full, clear, and exact description of the invention, such as will enable others skilled in the art to which it appertains to make and use the same.

This invention relates to a calculating machine with a series of keys, which differs from other similar machines by its being able to be operated practically without any expenditure of power and noiselessly. For the attainment of this object the shifting mechanism of the machine is operated by power, being normally held against movement and adapted to be released by finger pressure. Clockwork may, for instance, be employed as the source of power, but of course any other suitable source of power, such, for instance, as electricity and the like, may be employed instead of it.

The shifting mechanism according to the present invention consists substantially of a ratchet wheel the stop mechanism of which is released by the depression of a key and is turned sufficiently far to operate a calculating mechanism of any suitable kind to correspond with the figure value of this key. This movement is also limited by a pivoted pawl, which, on the release of the ratchet wheel, engages in its turn in catch teeth of the same and turns with it until it encounters the pin of the respective depressed key. After the release of the key all the shifting mechanisms return again automatically into the normal position. An arrangement is also provided for shifting the apparatus from the adding position into the subtracting position, which is operated by the interpolation of another transfer wheel.

One form of construction of the invention is more particularly shown as an example in the accompanying drawings.

Figure 1 is a plan view of the apparatus with the cover removed; Fig. 2, a front view; and Fig. 3, a rear view; while Fig. 4 is a side view; Figs. 5 and 6 are a plan view and front view respectively of the ratchet and releasing mechanism; Fig. 7 is a detail view of the member transmitting the key movement to the releasing mechanism; Figs. 8 and 9 are a front view and a side view, respectively, of

the releasing mechanism, on an enlarged scale; Figs. 10 and 11 are front views of the shifting device, on an enlarged scale, in the two positions of the parts thereof; Figs. 12 and 13 are plan and side views, enlarged, of the essential parts of the apparatus removed from the frame, certain parts of the shifting mechanism being omitted, and Fig. 14 is an enlarged plan view of a fragment of the machine showing particularly the calculating mechanism

The apparatus according to the present invention is a key apparatus and has, in this example of construction, nine keys 1, by the depression of which a calculating mechanism 2, itself of known type, is operated. The keys 1, on their depression, release a ratchet wheel 3 which acts on the calculating mechanism 2.

The ratchet wheel 3 is revolvably mounted in a frame 4 and is operated by any suitable source of power, such, for instance, as clockwork 5. For the purpose of arresting the wheel 3, it is provided on both faces with a ring of catch teeth 6 and 7, while in a position of repose a pawl 8 engages with the teeth 6 and thereby stops the wheel 3 in the position of repose. The pawl 8 is pressed by a spring 9 into the teeth 6 and is guided in a slotted socket or sheath 10 into which a forwardly pointing arm 11 projects. This extends up to beneath a bridge piece 12 which is vertically displaceably mounted on pins 13 (Fig. 6).

The bridge piece is under the action of a spring 14 and is pushed downward by pins 15 which are firmly connected with the keys 1 (Fig. 7). Now if a key be operated, its pin 15 presses back the bridge 12, which in turn presses back the pawl 8, that is to say, releases the wheel 3. The latter can now turn. In order to stop the wheel 3, after a rotation corresponding to the figure value of the respective depressed key, a pawl 16 is provided which is adapted to engage in the teeth 7. This pawl 16 is pivoted on the axis 17 of the wheel 3 and is returned by a spring 18 into a normal position. Further the pawl 16 is pivotal on a horizontal pin 19 and bears, with an extension or prolongation, against the bridge 12, so that it descends with the latter and comes into engagement with the teeth 7. Now if the wheel 3 be released, it turns together with the pawl 16 until the latter encounters the pin 15 of the depressed key 1. The movement is also so calculated

that only a rotation is possible corresponding to the figure value of the respective key. After the release of the key, the parts 8, 12 and 16, in consequence of the action of their springs 9, 14 and 18, respectively, again return to their normal position.

In order to be able to carry out various calculations such as addition and subtraction, a special shifting device is provided (Figs. 10 and 11). This consists of an adjusting lever 20 adapted to be stopped in any position, which lever is provided with an index or pointer 21 and by the help of a tablet 22 indicates the adjusted calculating operation. This lever is formed as a bell crank lever and is pivotal on a bolt 23 of the frame 4. With its free arm it engages a disk 24 of a gear or driving mechanism 25 which is displaceably mounted on an axis 26 which 10 transmits the rotary motion to the first pinion 31 of the calculating mechanism 2 (Figs. 10 and 11). Other pinions or gear wheels 28 and 29 are displaceably arranged on a second spindle 27, which wheels are moved 15 simultaneously with the wheel 25 by means of a friction disk 30 fast on the pinion 25. The pinion 28 is in constant gear with the pinion 25, while the pinion 29, for instance, engages with the ratchet wheel in the position 20 for subtraction. The direction of rotation of the spindle 26 is thus altered according as the wheel 3 is in engagement with the pinion 25 or the pinion 29.

The spindle 16 carries a pinion 31 which drives the calculating mechanism as follows: Pinion 31 meshes with a pinion 32 on a spindle 33 carrying a tooth 37 adapted, once in each revolution of spindle 33, to turn a pinion 38, loosely revolute on a spindle 38', one-tenth of a revolution; the pinion 38 meshes with a pinion 39 fast on a spindle 40 which carries a tooth 43 adapted, once in each revolution of spindle 40, to turn a pinion 44, loosely revolute on a spindle 44', one-tenth of a revolution; the pinion 44 meshes with a pinion 45, loosely revolute on a spindle 45'. The spindle 33 and 40 carry disks 34 and 41 on which are figures, from 0 to 9, which may be read through the openings 35 and 42. Above the openings 35 and 42 is arranged to move laterally a slide 48 provided with a horizontal row of apertures 48'. In this slide is journaled on the spindles 47 a series of pinions 49', 49², 49³, 49⁴, 49⁵, etc., 55 which carry disks 46 on which are numerals from 0 to 9; the pinions 49', 49², etc. are not connected with each other and are designed to be turned only when they mesh with the pinions 32, 39 and 45.

60 It will be obvious that with a mechanism comprising the parts 26, 31, 32, 33, 37, 38, 39, 40 and the disks 34 and 41, each time a key 1 is pressed, the spindle 26 will rotate a distance corresponding to the value of the 65 key; that, further once in every revolution

of disk 34, disk 41 will rotate one-tenth of a revolution. In this way, any amount up to 99 may be added. Subtraction will be accomplished in substantially the same way, except that, lever 20 being shifted, the spindle 26 and the train of mechanism which it controls will rotate in the reverse direction.

The purpose of the slide 48 and the mechanism carried thereby is to facilitate the calculations. At the openings 35 and 42 the operator needs to watch only the two right hand figures of a sum as the calculation proceeds. As each column of figures is added, and before starting to add the next column, the slide 48 is shifted to the right so that, for instance, instead of pinion 49' meshing with pinion 32, pinion 49² will now mesh with pinion 32, while pinion 49³ will mesh with pinion 39; the slide is shown in the new position in Fig. 14. Thus assuming we have a 85 column of figures, say, 68, 73, 44, 37 and 42, the slide being in its initial position and all the disks showing 0, upon adding 8, 3, 4, 7 and 2, 24 will appear at the openings 35 and 42, and also at the first and second right hand openings 48' in the slide. The slide is now moved one point to the right and the next column of figures 6, 7, 4, 3 and 4, is added. At the openings 35 and 42 will now appear 48, but at the three right hand openings in the slide will appear 264, which is the sum of the numbers which were to be added. Each time a fresh column is to be added the slide is moved one point to the right. Ordinarily, a column of figures will not total over 99, so that two openings 35 and 42 are sufficient; the machine of course may be constructed with three or more such openings and corresponding mechanism to accommodate columns of figures which would total 105 over 99. The number of the keys 1 and the figures may of course be any suitable one, so that suitable calculations may be carried out.

Preferably the entire apparatus is inclosed in a box with a lid adapted to lift up, so that 110 the apparatus is protected.

I declare that what I claim is:—

1. In a calculating machine, the combination, with a suitable support and a suitably driven rotary part normally actuated to rotate in a given direction, of a rectilinearly movable device normally acting to restrain said part against rotation; a rectilinearly movable member movable against said device to cause the same to release the rotary part, rectilinearly movable keys held normally spaced from said member but movable against the same to actuate it, and a fulcrumed part normally drawn in a direction opposite to the direction of rotation of said rotary part and movable between the same and the keys, said fulcrumed part having a ratchet-and-pawl engagement with the rotary part, substantially as described.

2. In a calculating machine, the combination,

tion, with a suitable support and a suitably driven rotary part normally actuated to rotate in a given direction and having a toothed periphery, of a device normally acting to restrain said part against rotation, a sliding member movable against said device to cause the same to release the rotary part, keys held normally spaced from said sliding member but movable against the same to actuate it, a fulcrumed part normally drawn in a direction opposite to the direction of said rotary part and movable between the same and the keys, said fulcrumed part having a ratchet-and-pawl engagement with the rotary part, a calculating mechanism, means, comprising intermeshing toothed rotary devices mov-

able together axially and alternately engageable with said rotary part and one of them being constantly engaged with the calculating mechanism, for transmitting the rotary motion in either direction from said rotary part to the calculating mechanism, and a lever operatively engaged with one of said devices and adapted to effect their axial movement, substantially as described. 20
